US00D858286S

(12) **United States Design Patent** (10) **Patent No.:** **US D858,286 S**
Blischak et al. (45) **Date of Patent:** **** Sep. 3, 2019**

(54) **STRUCTURED PACKAGING MATERIAL**

(71) Applicant: **Koch Knight, LLC**, Canton, OH (US)
(72) Inventors: **David Blischak**, Akron, OH (US); **Paul I. Rufener**, Rittman, OH (US)
(73) Assignee: **Koch Knight, LLC**, Canton, OH (US)
(**) Term: **15 Years**
(21) Appl. No.: **29/610,768**
(22) Filed: **Jul. 14, 2017**
(51) LOC (12) Cl. **09-07**
(52) U.S. Cl. **USPC D9/456**

(58) **Field of Classification Search**

(57) **CLAIM**

The ornamental design for a structured packaging material, as shown and described.

DESCRIPTION

FIG. 1 is a front left top perspective view of a structured packaging material showing our new design;

FIG. 2 is a top plan thereof;

FIG. 3 is a bottom plan view thereof;

FIG. 4 is a front elevation view thereof;

FIG. 5 is a rear elevation view thereof;

FIG. 6 is a left side view thereof;

FIG. 7 is a right side view thereof;

FIG. 8 is a front left top perspective view thereof, shown in a position of use with exemplary structured packaging material;

FIG. 9 is a front left top perspective view thereof, shown in a position of use with additional exemplary structured packaging material;

FIG. 10 is an enlarged view of a portion of the front top left perspective view shown in FIG. 1; and,

FIG. 11 is an enlarged view of a portion of the front elevation view shown in FIG. 4.

The broken lines represent environmental subject matter of exemplary structured packaging material and form no part of the claim.

1 Claim, 11 Drawing Sheets
